(57) **CLAIM**

The ornamental design for a curved wheel leveler, as shown and described.

DESCRIPTION

FIG. 1 is a left, front perspective view of a curved wheel leveler showing our new design;

FIG. 2 is a left, bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a partially enlarged view of FIG. 4.

The broken lines shown on the drawings depict portions of the curved wheel leveler that form no part of the claimed design
